UNITED STATES PATENT OFFICE

113,040

DESIGN FOR A COMBINED POTATO PEELER HANDLE AND SHREDDER

Albert H. Johnson, Detroit, Mich.

Application August 24, 1938, Serial No. 79,535

Term of patent $3\frac{1}{2}$ years

To all whom it may concern:

Be it known that I, Albert H. Johnson, a citizen of the United States, residing at Detroit, in the county of Wayne and State of Michigan, have invented a new, original, and ornamental Design for a Combined Potato Peeler Handle and Shredder, of which the following is a specification, reference being had to the accompanying drawing, forming part thereof.

In the drawing:

I claim:

The ornamental design for a combined potato peeler handle and shredder, as shown.

ALBERT H. JOHNSON.
